US00D604362S

(12) United States Design Patent
Suero, Jr. et al.

(10) Patent No.: US D604,362 S
(b4) Date of Patent: * Nov. 17, 2009

(54) WRITING INSTRUMENT

(75) Inventors: Jose Suero, Jr., Boca Raton, FL (US);
Li Bin, Ningbo (CN)

(73) Assignee: Office Depot, Inc., Boca Raton, FL (US)

() Term: 14 Years

(21) Appl. No.: 29/311,109

(22) Filed: Dec. 23, 2008

(51) LOC (9) Cl. 19-06

(52) U.S. Cl. D19/50

(58) Field of Classification Search D19/35, D19/36, 41-51, 53-57; 24/11 F, 11 P, 11 R; 401/52, 99, 100, 104-109, 192, 195, 196

See application file for complete search history.
